(57) CLAIM

The ornamental design for a barbell plate, as shown and described.

DESCRIPTION

FIG. 1 is a front elevational view showing my new design for a barbell plate;

FIG. 2 is a side elevational view of the barbell plate shown in FIG. 1;

FIG. 3 is a front perspective view of the barbell plate shown in FIG. 1;

FIG. 4 is a front elevational view of a second embodiment of a barbell plate showing my new design;

FIG. 5 is an end elevational view of the barbell plate shown in FIG. 4; and,

FIG. 6 is a front perspective view of the barbell plate shown in FIG. 4.

The opposite side of the barbell plate shown in FIG. 1 is the mirror image thereof and the opposite side of the barbell plate shown in FIG. 4 is the mirror image thereof.
